Attorney.

UNITED STATES PATENT OFFICE.

EROL V. HOUGHTON, OF SYRACUSE, NEW YORK.

CAN OPENER.

Application filed August 31, 1927. Serial No. 216,753.

The invention relates to can openers, and has for its object to provide a simple and inexpensive opening device, which may be permanently mounted on the heads of fruit, 5 or other sealed tin cans, ready for instant use, the said opener being arranged to lie within the usual recess or depression of the head-end of a can, and to be rotated manually for cutting out a circular section of the head 10 for enabling the contents of the can to be extracted. The opener comprises a single strip of flexible metal, such as cold rolled steel or the like, said strip being formed with an integral cutting-spur preparatory 15 to being folded and applied to the head of the can, said spur being located adjacent the fold, and the fold being effected in such manner as to provide a relatively short radial arm, whose free end is formed with a reduced 20 offset portion, which may be inserted through a central opening in the head, the said opening cooperating with said offset, for supporting as well as for rendering the opener rotatable during the cutting operations, the 25 metal comprising the opener being sufficiently pliable to enable the longer arm or handle to be flexed or bent away from the short arm for disposing the spur in the cutting position, the operator being required 30 first to depress the handle until the spur pierces the head adjacent the bead that defines the said recess, after which the handle may be bent downwardly and outwardly and finally rotated for effecting the circular cut 35 out which enables the contents of the can to be removed.

I attain these objects by the means set forth in the detailed description which follows, and as illustrated by the accompanying 40 drawing, in which—

Figure 1 is a top plan view of a can, showing the opener in its operative position. Fig. 2 is a similar view, showing the longer arm of the opener disposed vertically, the first 45 step in the opening operation. Fig. 3 is a broken central vertical section taken on line 3—3 of Fig. 2, showing the cutting-spur in the act of piercing the head of the can. Fig. 4 is a similar view showing the long arm 50 of the opener extended horizontally ready to be rotated for cutting a circular opening in the head. Fig. 5 is a side elevation of the opener shown in Fig. 1. Fig. 6 is an enlarged broken sectional view, showing the 55 central opening that receives the pivot-lug closed by solder. And Fig. 7 is a top plan

view of the blank from which the opener is formed.

In the drawing, 2 represents the cylindrical body of an ordinary tin can, having a normally open top-end 2', which is shown closed by a head or cap 3, the latter usually being clinched to the end 2', in a manner to form an annular bead 3' that defines the usual shallow recess 3", and the head 3 preferably being formed with a relatively small central perforation 3'.

My improved can opener comprises a relatively thin flat strip of flexible metal 4, such as cold rolled steel or the like, which is 70 capable of cutting the relatively tough web of the head 3, the said strip being formed at one end with reduced dull-pointed portion 4', which is offset, as shown in Figs. 3, 4, 5, 6 and 7, and inserted through the opening 3", 75 for loosely interlocking the said parts. Beyond the offset end the strip 4 is sheared for providing a V-shaped cutting-spur 5 (see Fig. 7), after which the strip is folded upon itself adjacent the said spur, as best seen in Figs. 1 and 5. This folding preferably 80 provides a short arm 6, which lies beneath a relatively long arm 7, and when the device is applied to the head 3, both of said arms preferably lie below the plane of the bead 85 3'. By this arrangement, a number of the cans equipped with the attached opener may be readily and safely stacked without interference by or danger of injuring the opening device. In practice, when the opener 4 is applied to the head 3, as shown in Fig. 1, 90 the manufacturer secures the offset 4', by means of a drop of solder, as 8, as best seen in Fig. 6. The solder should be so applied so as to effectually seal the opening 3", to prevent leakage or spoiling of the contents of 95 the can. The can may then be handled the same as heretofore without danger of the opener becoming accidentally displaced. When the strip 4 is properly folded, the cutting-spur 5 becomes extended substantially in the plane of the long arm or handle 7, as shown in Figs. 1 and 5, where it remains until the cutting operation begins. To open the can 100 2, the first step consists of the operator grasping the free end of the handle 7 and swinging said part upwardly, to the position shown in Figs. 2, 3 and 6, which act may be readily accomplished by the flexing of the metal in the vicinity of the bend 4'. 105 This correspondingly shifts the cutting-spur 5 from the horizontal to the vertical position,

and disposes the said spur directly over an annular depression 3^d of the head adjacent the bead $3'$, and at a point where the head is stiffened by the proximity of said depression to the bead. When heavier gage tin is used the gage of the annular depression 3^d may be reduced by the dies that form-up the head, for facilitating the cutting by the spur 5 , in a well-known manner. The operator next exerts sufficiently downward pressure on the handle 7 , to cause the spur to pierce the head, as shown in Figs. 3, 4 and 6. This latter operation may be readily effected since the head 3 is usually only a few thousandths of an inch in thickness. Immediately following the piercing of the head, the operator again swings the handle 7 outwardly and downwardly, as shown in Fig. 4. This disposes the handle substantially in the plane of the arm 6 , and provides ample leverage to enable him to rotate the opener on the pivot $3^e-4'$, for effecting a circular cut in the path defined by the depression 3^d . This final operation may be greatly facilitated by the operator exerting sufficient downward pressure to maintain the frictional contact of the handle with the bead $3'$. In case the handle 7 is rotated a full turn, a circular section of the head will be severed and may be removed and discarded together with the opener, thereby enabling the contents of the can to be readily and quickly removed. The solder 8 should be preferably relatively soft, so as to enable the offset portion $4'$ to break the seal and allow the opener to be freely rotated.

Having thus described my invention, what I claim, is—

1. A can opener arranged to be permanently mounted upon the head of a can, comprising a strip of flexible metal folded upon itself to provide a long and a short arm, the free end of the short arm adapted to pivotally engage the central portion of the head of the can, said strip being sheared adjacent the fold for providing a cutting-spur that projects beyond the bend adapted when the long arm is swung from the horizontal to the vertical position to pierce the head adjacent its periphery, and said long arm adapted when bent forwardly and downwardly to be rotated for causing the said spur to cut a circular opening in the head.
2. A can opener permanently mounted

upon the head of a can, comprising a strip of flexible metal folded upon itself to provide a long and a short arm, the latter having an upset portion adapted to engage a central opening in the head, means for closing said opening and preventing detachment of the opener; said strip being sheared adjacent the fold for providing a cutting-spur adapted when the strip is folded to project beyond the bend and to lie in the plane of the long arm, said long arm adapted to be swung upwardly to enable the spur to pierce the head, and said long arm adapted to be bent forwardly and downwardly and then rotated for cutting a circular opening in said head.

3. A can opener affixed to the head of a can formed with a central perforation, comprising a strip of flexible metal bent upon itself to form a short and a long arm adapted to be disposed diametrically across the head of the can, the short arm having an upset portion adapted to pivotally engage the said perforation and having an integral cutting-spur formed adjacent the said fold adapted when the long arm is swung upwardly and subjected to downward pressure to pierce the head adjacent its periphery, and said arm adapted to be extended horizontally beyond the can and rotated substantially in the plane of the head for enabling the spur to sever a circular section from the head.

4. A can opening device comprising a strip of flexible metal having an offset portion at one end adapted to pivotally engage an opening in the head of a can, said strip being sheared near its middle to provide a pointed cutting-spur, the portion of said strip beyond said spur being folded towards and overlying said offset to provide a handle, said strip when folded adapted to be disposed within a depression in the head of the can, said handle adapted to be swung upwardly by flexing the metal of said fold for disposing the cutting-spur vertically in contact with the head adjacent its periphery, adapted when the handle is depressed to pierce the head, and said handle adapted to be swung outwardly and downwardly beyond the can and to be rotated on the said pivot for cutting a circular section from the head.

In testimony whereof I affix my signature.

EROL V. HOUGHTON.
